UNITED STATES PATENT OFFICE.

WILLIAM NORMAN, OF WESTON-SUPER-MARE, ENGLAND.

TROUSERS SUPPORT AND THE LIKE.

1,403,974.

Specification of Letters Patent. Patented Jan. 17, 1922.

Application filed December 14, 1920. Serial No. 430,751.

To all whom it may concern:

Be it known that I, WILLIAM NORMAN, subject of the King of Great Britain and Ireland, residing at "Cliftonville," Locking 5 Road, Weston-Super-Mare, in the county of Somerset, England, have invented certain new and useful Improvements in Trousers Supports and the like, of which the following is a specification.

10 My invention relates to a new or improved device or appliance for supporting trousers and the like wearing apparel of the type adapted to be supported at the waist.

15 The object of the invention is to provide an easily manipulated device or appliance which will support such articles with more comfort to the wearer, which will allow more freedom of movement and which may be easily adjusted to suit the girth of the 20 wearer and at the same time effectively support the garment without imparting unnecessary strain on the material thereof, as is often the case with the usual type of brace.

25 According to the invention, the device or appliance comprises two or more bands, strips or the like connected together by one or more non-elastic strips, provided with adjusting means in the form of a buckle or 30 the like. The outer free ends of the strips or bands are each provided with one or more loops or perforated or slotted tabs or the like co-operating with buttons or other means on the trousers, said buttons being located towards opposite sides and at the 35 waist, preferably in the neighborhood of the side pockets or seams.

In the preferred construction according to the invention, the bands, strips or the 40 like carrying the loops are formed of elastic material of suitable width and length, and each may be formed in one or more strands or of one or more thicknesses of material. The outer ends of the elastic bands are provided with loops or the like, preferably secured to transverse strips sewn or otherwise fastened or incorporated with the ends of the elastic bands so as to constitute at 45 the same time binding strips therefor to prevent fraying.

The inner ends of each of the elastic bands are each attached as by sewing to a second band or strip of non-elastic material, such as canvas, soft leather, or any other suitable 50 material. The inner ends of the elastic strips may be drawn towards one another by

a single non-elastic strip or by separate strips, one of which carries a buckle with which the free end of the other engages, or any other suitable fastening or adjusting 60 means may be employed.

The various bands or strips may be doubled upon themselves and connected together by links or slotted plates of metal or other material.

65 In order that the invention may be readily understood reference is made to the accompanying drawings in which:

Fig. 1 is a front elevation showing the upper portion of a pair of trousers with the 70 improved supporting appliance attached thereto.

Fig. 2 is a similar view seen from the rear.

Fig. 3 is a perspective view to a larger 75 scale of the supporting appliance.

The device comprises a pair of bands or strips or the like *a*, *b* of elastic material which are made of suitable width and length. The outer ends of each of these 80 bands have secured thereto a pair of loops *c*, *c*, which may be attached in any suitable manner as by sewing or the like, the ends of the elastic bands being preferably provided with transverse non-elastic strips *d* which 85 form a binding for the ends of the bands.

The inner ends of the bands *a*, *b* are also each preferably provided with transverse binding strips *e*, *e*, to which are secured the ends of strips or bands *f*, *g* of non-elastic 90 material. The strip *f* is comparatively short in length and has secured to its free end a buckle *h* while the band *g* is of any convenient length to enable the length of the device between the loops at opposite ends 95 to be adjusted within pre-determined limits.

The non-elastic strip *f* may be provided with one or more loops or the like *k* through which the free end of the strip *g* is passed when the same has been adjusted within the 100 buckle.

The trouser or other garment *m* with which the supporting device is used, is provided in the neighborhood of the waist line and on opposite sides with buttons or the 105 like *n* over which the loops *c*, *c* engage, as shown in Fig. 1. The buttons are located one above the other, preferably in close proximity to the side pockets or side seams of the garment, but they may, of course, be 110 located just above the top of the pocket or slightly to the rear thereof if desired. Or

if desired the elastic bands carrying the loops may be extended towards the front, the buttons or the like being similarly located.

5 It will be understood that any number of loops may be provided at the ends of the elastic strips.

If desired the transverse strips *d* and *e* may be replaced by metallic loops or slotted 10 plates, the elastic bands *a*, *b* or the non-elastic strips *f*, *g* being, if desired, formed as endless bands passing through said loops or slotted plates. Again the strips *f*, *g* may be replaced by a single strip, one end of 15 which carries a buckle, the strips *e*, *e* being replaced by slotted members through which the opposite end of the single strip is passed before being engaged with the buckle.

I claim:—

20 1. A supporting device for trousers and the like wearing apparel comprising a pair of bands each adapted to be detachably connected at one end to buttons or the like on the garment and provided at their other

ends with means whereby they may be detachably secured together, each of said bands consisting of two portions, one a portion of elastic material having a free end to which is attached a loop or loops, and the other a portion of non-elastic material, said two portions being connected together by means of an intermediate transverse strip of non-elastic material.

2. A supporting device for trousers and the like wearing apparel, consisting of two 35 parts detachable from each other, each of said parts comprising a band of elastic material, transverse binding strips sewn to opposite ends of each of said bands, a pair of loops secured to the binding strips at the 40 outer ends of said bands, strips of non-elastic material secured to the inner ends of said elastic bands, and a buckle on the free end of one of said last mentioned strips adapted to be engaged by the free end of 45 the other of said last mentioned strips.

WILLIAM NORMAN.
